INVENTOR:

Jacob Vreeland

UNITED STATES PATENT OFFICE.

JACOB VREELAND, OF SADDLE RIVER, BERGEN COUNTY, NEW JERSEY.

RAILROAD-CO尤LING FOR RAILS.

SPECIFICATION forming part of Letters Patent No. 340,742, dated April 27, 1886.

Application filed September 9, 1885. Serial No. 175,960. (No model.)

To all whom it may concern:

Be it known that I, JACOB VREELAND, a citizen of the United States, residing in the township of Saddle River, in the county of Bergen and State of New Jersey, have invented a new and useful Improvement of a Railroad-Coupling for Rails, styled a "Coupling-Plate;" and I declare that the following is a full, clear, and exact description of the construction and operation of the same, reference being had to the annexed drawings, making a part of this specification, in which—

Figure No. 1 represents an upright drawing of the rail with the coupling attached, with 15 horizontal bolts, one on either end of the rails, coupled by the plate. Letter A represents the rails. Letter B represents the plate; letters D D, extension on plate; letter E, the platform on which the ends of the rails rest. 20 Letters a a represent the rails as adjusted by the coupling; letters b b, the foot of the rails; letters c c, the tops of the rails in their position as to the coupling-plate; letters d d, the nut adjusting and holding the bolt; letters e e, the washer between the nut and the 25 plate; letters f f, the bolt fastening the coupling-plate to the rail.

Fig. No. 2 represents section on line Z Z, as

shown in Fig. No. 1, the letters, both capital and small, bearing the same representations as 30 in Fig. No. 1; Fig. No. 3, plan of under side, the letters used bearing same representations as in Fig. No. 1; Fig. No. 4, section on line x x, letters B, D, and E bearing the same representation as in Fig. No. 1, and the letter F 35 representing the bolt-holes.

Fig. No. 5 represents the front view of the plate, letters bearing the same representation as in Figs. Nos. 1 and 4.

What I claim, and desire to secure by Letters Patent, is—

The coupling-plate consisting of the vertical part B, extended obliquely to overlie the foot of the rail, and having its lower intermediate part folded to fit beneath the rail, and its lower 45 end parts extended laterally to rest upon the ties, the vertical parts being adapted to be bolted through the web of the rail, substantially as set forth.

In witness whereof I have hereunto set my 50 signature this 13th day of February, A. D. 1886.

JACOB VREELAND.

In presence of—

CHARLES H. HARDER,
DAVID J. BERRY.
